(57) **CLAIM**

The ornamental design for a connector module, as shown.

DESCRIPTION

FIG. 1 is a front, top perspective view of a connector module, showing our new design;

FIG. 2 is a side elevation view thereof;

FIG. 3 is a rear elevation view thereof;

FIG. 4 is a front elevation view thereof;

FIG. 5 is a top plan view thereof; and,

FIG. 6 is a bottom plan view thereof.

The broken lines in the drawings depict environmental subject matter only and form no part of the claimed design. The dot-dashed lines are a drafting convention to identify the part of the article in which the claimed design is embodied.
